CHAIR ATTACHMENT

Lulu Elizabeth Kynce, Sacramento, Calif.

Application September 26, 1941, Serial No. 412,485

1 Claim. (Cl. 155—127)

The present invention relates to improvements in chair attachments for converting a chair of ordinary construction to a chair for use by babies and children during feeding.

The primary purpose of the invention is to provide an attachment comprising a tray and back member which is adapted to be secured to the conventional chair so that the chair may be used for children in lieu of the costly high-chair now commonly used.

A still further object of the invention is to provide a frame which may be removably attached to a chair for supporting an adjustable tray and backing member so that the child user will be required to sit forwardly in the chair and close to the tray.

Other objects and advantages of the invention will become apparent during the course of the following description of the accompanying drawing, wherein,

Figure 1 is a side elevational view of a conventional chair illustrating the attachment in side elevation secured thereto;

Figure 2 is a front elevational view of the device embodying the invention, illustrating the same applied to the conventional armless chair;

Figure 3 is a vertical cross-sectional view taken on line 3—3 of Figure 1, looking in the direction of the arrows, illustrating in detail, the manner in which the tray is adjustably supported;

Figure 4 is a vertical cross-sectional view taken on line 4—4 of Figure 1, looking in the direction of the arrows, showing the manner in which the seat back is also adjustably secured to the detachable frame;

Figure 5 is a top elevational view of the frame or attachment removed from the chair; and

Figure 6 is a bottom plan view of the tray showing the same removed from the frame.

In the drawing, wherein for the purpose of illustrating the invention and wherein like reference characters will be employed to designate like parts throughout the same, the reference character 5 will generally be employed to designate a chair having a pair of front legs 6 and rear legs 7 continued upwardly as at 8 to form the framework for a back. A seat 9 connects the legs 6 and 7 and the legs are braced by rounds 10. The back formed by the continuations of the legs, as at 8, are connected as at 11 and 12 by horizontal back members and the horizontal back members are connected by a relatively wide back strip 13.

The above structure is typical of a present-day armless chair such as is used in dining rooms.

The invention comprises a rectangular frame formed of tubular metal comprising parallel side bars 14 connected at one end, as at 15, by a similarly formed tubular member or bar. The parallel side bars 14 are spaced a distance slightly smaller than the width of the chair seat 9 so that the frame bars will be substantially within the confines thereof. The opposite ends of the parallel bars 14 are return bent as at 16 and terminate in a U-shaped portion 17. At the bend 16, a tubular frame member 18 is adapted to connect each of the side frame bars 14 and said connecting bar 18 is welded or otherwise secured in place and is adapted to hold the forward ends of the rectangular frame in equi-distantly spaced relation.

The lower leg of the U-shaped portion 17 is adapted to receive one end of an angular foot member 19 which is round in cross section and 20 is substantially the same diameter as the bore in the tubular member 17 so that the parts may be inter-fitted and held in place by a screw 20 passing through the tubular member and having its end engaging the foot member 19.

25 The lower end of the foot member 21 is adapted to rest on a forward corner of the chair seat 9 and may be attached thereto by passing a flexible element 22 through an opening in the foot member 21 and around the forward leg 6.

30 Similarly, the rear ends of the frame bars 14 may be apertured as at 24 for receiving a flexible tying element 25 which may be passed around the chair back rails 8 as shown in Figure 1.

Slidably mounted between the forward ends 35 of the parallel frame bars 14 is a tray 26 having a marginal upstanding flange 27 to prevent displacement of articles such as dishes and the like from being thrown from the tray and each end of the tray is provided with loops 28 which are 40 adapted to encircle the frame bars 14 so that relative sliding movement therebetween may be had for the purpose of adjusting the tray longitudinally of the frame. A set screw 29 is threaded in the loop 28 to anchor the tray against movement when the same has been adjusted to its desired position. The rear edge of the tray 26 may be curved as at 30 so that the tray may be 45 pushed rearwardly into close contact with the child to prevent drippings and the like from falling on the floor or in the lap of the child.

Slidably mounted between the rear ends of the parallel tubular side bars 14 is an adjustable back 31 having secured adjacent each end thereof outwardly extending lugs 32, held in place by 50 screws or the like, as at 33. The free end of the

lug 32 is provided with a tubular slide 34 which is free to move on a tubular side bar 14 and is adapted to be held in an adjusted position by means of a set screw 35 threaded therein so that the inner end will frictionally engage the tubular bar. The lower end of the back 31 is adapted to rest on the rear end of the chair seat 9 while the upper edge of the back 31 is adapted to rest on the vertical chair back piece 13 in the rear-most position of the back 31. A strap 36 has its ends connected to the sides of the back 31 and is provided with a buckle 37 for adjusting the length of the strap which is adapted to encircle the child and hold the child in the chair. The chair back 31 may be slid forwardly if desired so that the child's legs will hang over the forward edge of the chair seat 9 and the back 31 will provide sufficient resting surface in the proper position for the child's back. After the back has been adjusted, the tray 26 may be adjusted so that the child will properly sit while feeding or being fed.

It is to be understood that the form of the invention herewith shown and described is to be taken as the preferred embodiment of the same and that various changes in the shape, size and arrangement of parts may be resorted to without departing from the spirit and scope of the invention as claimed.

I claim:

10 A chair attachment comprising a tubular frame having parallel side bars, a rear bar connecting the side bars, the forward ends of the side bars being downwardly and reversely bent, vertical foot portions connected to the reversely bent frame portions, a front cross bar connecting the downwardly bent portions, a tray slidably connected to the forward ends of the side bars, an auxiliary back rest slidably connected to the rear ends of the side bars, and means detachably connecting the rear of the frame to the chair and the lower ends of the foot portions to the front of the chair.

LULU ELIZABETH KYNCE.
